INSULATED JUG

David Edward Roche, Nashua, N.H., assignor to Family
Products, Inc., Tyngsboro, Mass.

Filed Sept. 27, 1972, Ser. No. 292,779

Term of patent 14 years

Int. Cl. D7—01

U.S. Cl. D7—77

FIG. 1

FIG. 2

FIG. 3

FIG. 4

FIG. 5

FIG. 6

FIG. 1 is a perspective view of an insulated jug embodying my new design;

FIG. 2 is a top plan view thereof, the handle being in a pivoted horizontal position;

FIG. 3 is a bottom view thereof;

FIG. 4 is a perspective view of the insulated jug of FIG. 1 showing a modification of my new design;

FIG. 5 is a top plan view of the design of FIG. 4, the handle being in a pivoted horizontal position; and FIG. 6 is a bottom view thereof.

I claim:

The ornamental design for an insulated jug, as shown and described.
